CARRIER FOR STORAGE BATTERIES

Joseph Mistrett, Buffalo, N. Y.

Application February 9, 1937, Serial No. 124,935

6 Claims. (Cl. 294—104)

This invention relates to a storage battery carrier and more particularly to a carrier which is readily attached to and permits the manual lifting of batteries and transporting them and consisting generally of a strap of insulating material having gripping means at each end adapted to engage the two terminals of the storage battery.

One of the objects of the invention is to provide such a battery carrier in which the gripping means are readily applied to the terminals of the battery and which, upon lifting the applied strap, firmly and reliably grip the terminals to permit of lifting the battery even though the terminals may vary as to size and may be quite tapered.

Another object of the invention is to provide such a battery carrier which is very inexpensive in construction and includes no parts which are liable to wear and get out of order.

In the accompanying drawing:

Fig. 1 is a fragmentary elevational corner view of a storage battery showing my carrier applied thereto.

Fig. 2 is a fragmentary top plan view of the battery carrier.

Fig. 3 is a vertical longitudinal section taken on line 3—3, Fig. 2 and showing the manner in which the gripping means engage the battery terminal.

The carrier forming the subject of my invention is illustrated in connection with a conventional storage battery having the usual hard rubber case 5 and positive and negative terminals 6, 7. The construction of the conventional storage battery is such that the battery can be lifted and transported by gripping the two terminals 6 and 7.

The carrier includes a flexible strap 8 which can be made of any insulating material, such as rubber, and at each end is provided with a gripping device adapted to engage one of the terminals 6, 7. These gripping devices are identical in construction and the description of one will be deemed to apply to both.

To each end of the strap 8 is secured a folded metal strip the opposite ends 10, 11 of which are shown as riveted to the opposite sides of the strap, as indicated at 12. The folded end of the strip extends beyond the end of the strap, as indicated at 13 and the extension 13 is disposed at an angle to the attaching portion 10 and 11, as best illustrated in Fig. 3 so that when the extension 13 is horizontal, the attaching portions 10, 11 extend upwardly. The fold of the strip is formed to provide a pair of spaced eyes 14, 15 and the metal originally between the eyes 14 and 15 is bent

upwardly to form an upwardly inclining jaw 16. The end of the jaw 16 is preferably curved as indicated at 17 and is also formed to provide a lower sharp edge 18.

The battery terminal is embraced by a ring member 20 which is generally of horseshoe-shaped form having a curved portion 21 and side legs 22 connected by a cross bar 23. The cross bar 23 is arranged in the two eyes 14 and 15 and is free to move therein. The curvature of the outer end 10 of the ring is preferably of parabolic form so that when a battery terminal is gripped between the jaw 16 and the curved portion 21 of the ring, it is always engaged at three points regardless of the sizes of the battery terminal, the parabolic 15 form of the ring insuring its two-point engagement with the terminal regardless of its size, as best illustrated in Fig. 2.

In applying the battery carrier the garage mechanic slips the two rings over the terminals 6, 7 and lifts the strap 8. As he lifts the strap 8 the rings 20 are drawn together and the jaws 16 are swung downwardly into engagement with the inner faces of the terminals 6, 7 the edges 18 digging into the terminals so as to secure a firm grip. The greater the weight of the battery the more the jaws 16 dig into the terminal and since the jaws 16 project upwardly it will be seen that they directly and positively oppose the downward movement of the battery. It will, therefore, be seen that by forming the jaw 16 to project upwardly the carrier is quick, positive and self-gripping in its action and the jaw exerts a positive toggle action in gripping the terminals.

From the foregoing it will be seen that the present invention provides a very inexpensive and easily manufactured article the more particularly in that each gripper is composed of but two parts and the connecting eyes and the jaws can be formed by a very simple stamping operation. Further it will be seen that since the downward pressure of the suspended battery tends to cause a downward movement of each jaw the grippers are self-gripping and positively engage the terminals so that there is no danger of the battery slipping, regardless of its weight.

I claim as my invention:

1. A storage battery carrier, comprising a strap and a gripper at each end of said strap adapted to fit over and grip one of the terminals of the battery, each of said grippers including a folded strip of metal the fold of which provides a horizontal extension and the legs of which extend inwardly and upwardly from said horizontal extension and are secured to the opposite sides of

the strap, said horizontal extension being formed at its fold to provide an upwardly and outwardly extending jaw, and a ring member loosely connected to said horizontal extension, the corresponding terminal of said battery being caught between said ring member and jaw whereby upon lifting said strap said jaw is swung downwardly to firmly engage the battery terminal.

5 2. A storage battery carrier, comprising a strap 10 and a gripper at each end of said strap adapted to fit over and grip one of the terminals of the battery, each of said grippers including a folded strip of metal the fold of which is formed to provide an eye and an outwardly extending jaw and the legs of which extend inwardly from said fold and are secured to the opposite sides of the strap, a ring member loosely secured in said eye and being adapted to fit over the corresponding terminal of said battery, said jaw being disposed 15 at such an angle relative to said legs that upon lifting said strap said jaw is swung to firmly engage the battery terminal.

3. A storage battery carrier, comprising a strap 20 and a gripper at each end of said strap adapted to fit over and grip one of the terminals of the battery, each of said grippers including a folded strip of metal the fold of which is formed to provide a pair of eyes and the material originally between said eyes being formed to provide a jaw 25 extending outwardly from said fold and the legs of said strip being secured to the opposite sides of the strap and a ring member loosely secured in said eyes and being adapted to be fitted over the corresponding terminal of said battery, said jaw being at such an angle to said legs that upon lifting said strap said jaw is swung to firmly engage the battery terminal.

4. A storage battery carrier, comprising a strap 30 and a gripper at each end of said strap adapted to fit over and grip one of the terminals of the battery, each of said grippers including a folded strip of metal the fold of which provides a horizontal extension and the legs of which extend inwardly and upwardly from said horizontal extension and are secured to the opposite sides 35 of the strap, said horizontal extension being

formed at its fold to provide a pair of spaced eyes and the material originally between said eyes being formed to provide an upwardly and outwardly extending jaw and a ring member loosely secured in said eyes and adapted to fit 5 over the corresponding terminal of said battery whereby upon lifting said strap said body is swung downwardly to firmly engage the battery terminal.

5. A storage battery carrier, comprising a strap 10 and a gripper at each end of said strap adapted to fit over and grip one of the terminals of the battery, each of said grippers including a folded strip of metal the fold of which provides a horizontal extension and the legs of which extend 15 inwardly and upwardly from said horizontal extension and are secured to the opposite sides of the strap, said horizontal extension being formed at its fold to provide a pair of spaced eyes and the material originally between said eyes being 20 formed to provide an upwardly and outwardly extending jaw and a ring member having a cross bar loosely mounted in said eyes and being adapted to fit over the corresponding terminal of said battery whereby upon lifting said strap said jaw 25 is swung downwardly to firmly engage the battery terminal, and the portion of said ring member opposite said jaw being of parabolic form whereby said terminal is engaged at three places by said ring member and jaw.

6. A storage battery carrier, comprising a strap 30 and a gripper at each end of said strap adapted to fit over and grip one of the terminals of the battery, each of said grippers including a strip of metal directly secured to the corresponding 35 end of said strap, a jaw formed integrally with said strip and extending outwardly and upwardly from said strip, and a ring member loosely connected to an eye formed in said strip at the base of said jaw, said jaw extending a short distance 40 across the opening in said ring member, the corresponding terminal of said battery being caught between said ring member and jaw whereby upon lifting said strap said jaw is swung downwardly to firmly engage the battery terminal.
